UNITED STATES PATENT OFFICE

CLAUDE R. KIRK, OF CHICAGO, ILLINOIS

DESIGN FOR AN AMUSEMENT MACHINE CABINET

Application filed August 8, 1932. Serial No. 44,545. Term of patent 7 years.

To all whom it may concern:

Be it known that I, CLAUDE R. KIRK, a citizen of the United States, residing at Chicago, in the county of Cook and State of Illinois, have invented a new, original, and ornamental Design for Amusement Machine Cabinets, of which the following is a specification, reference being had to the accompanying drawing, forming a part thereof in which the figure is a perspective view of the cabinet.

I claim:

The ornamental design for an amusement machine cabinet as shown.

CLAUDE R. KIRK.
